CAR MOVING DEVICE

Application filed June 4, 1923. Serial No. 282,601.

32

This invention relates to railway car moving devices and particularly to the hand operated type which is positioned on the rail beneath the car wheel and operated to force the car wheel forward.

An object of this invention is to provide a car moving device having a base on which is fulcrumed a lever having a roller adapted to contact with the periphery of the car wheel to move the car as said roller is oscillated by means of a long lever arm.

A further object of the present invention is the contemplation of a car moving device having means for preventing backward slipping of the device on the rail when the same is being operated.

Further objects of this invention are simplicity of construction, ease of operation and durability.

20 With these general objects in view, as well as minor objects which will appear during the course of the detailed specification, the invention will now be described with reference to the accompanying drawings, wherein

25 Figure 1 is a car moving device embodying this invention shown in the operative position on a rail.

Fig. 2 is an enlarged fragmentary sectional view of Fig. 1.

30 Fig. 3 is a horizontal section taken on line III—III of Fig. 2, and

Fig. 4 is an inverted plan of the base.

Similar reference characters designate like parts throughout the several views, and the 35 numeral 10 designates a base having upturned lugs 11 in which is mounted a bolt 12 which serves as a fulcrum for the lever 13. The base 10 is provided with downwardly projecting portions 14 and 15, which are positioned respectively at the front and rear extremities thereof.

For the purpose of preventing backward movement of the base 10 when in the operative position, there is provided a rearwardly 40 extending ratchet tooth 16, preferably made of tool steel and securely mounted in a dovetailed groove 17, formed in the lower side of base 10. A set screw 18, is adapted to engage tooth 16 to prevent longitudinal movement thereof.

As clearly shown in Fig. 2, it will be noted that the ratchet tooth 16 extends below the plane of the downwardly projecting portions 14 and 15 so that when the base is positioned on top of the rail R, the tooth 16 will contact with said rail in such a manner as to prevent a backward movement of the moving device when the same is being operated to move the car forward, as hereinafter described.

Should an excessive weight be exerted on the device to cause the ratchet tooth 16 to be imbedded too far into the rail, the downwardly extending portion 15 would contact the upper surface of said rail to prevent undue cutting thereof, and yet at the same time allow the ratchet 16 to be imbedded sufficiently to prevent any backward movement of the device on the rail. The ratchet tooth 16 may be replaced by a transversely serrated plate or any other suitable roughened surface which would permit a forward movement of the device and prevent backward movement thereof.

The vertical plane of the axis of the bolt 12 to the surface of the rail is intermediate the downwardly extending portion 14, and ratchet tooth 16, thereby causing 14 and 16 to normally carry the weight exerted on bolt 12 when the device is in operation. However, in the operation, it has been found desirable to provide the downwardly extending portion 15 to prevent any accidental movement of the forward end of the base 10 upwardly to engage the periphery of the car wheel W.

The lever 13 is of the ordinary first class type, being fulcrumed intermediate its ends on the bolt 12, and having a short arm 19 and a long arm 20. The short arm 19 extends forwardly and is provided with a roller 21 which is rotatably mounted on a pin 22 carried by the two arms 23 of the bifurcated portions of arm 19. To obviate rocking of the base plate it will be noted that the roller 21 is positioned above and intermediate the supporting portions of the base. The long arm 20 of the lever 13 may be made in one unit or in two units, as shown. The tapered socket 24 formed in the long arm 20 of lever 13 is adapted to receive the tapered end 25 of a handle 26. This construction permits

100

- of the removal of the handle for the purpose of inserting longer or shorter handles, and also facilitates in the packing of the device for shipment. To prevent undue wear of the contacting parts, it is desirable to make the ratchet tooth 16 and roller 21 of hardened steel. These parts may be replaced in case of excessive wear, thereby prolonging the usefulness of the device.
- 10 In the operation of this device, the operator grasps the handle 26 and places the base 10 on the rail R in a position as shown in Fig. 1. He then presses downwardly on the handle to the position shown in dotted lines so that the roller 21 is moved in an arc about the bolt 12, and the roller 21 contacts with the periphery of the wheel W, thereby forcing the wheel forward. The operator then raises the handle 26 and moves the device forward until it is again in the operative position, with the roller 21 contacting with the periphery of the wheel W and the operation is repeated, until the car has been moved to its desired destination.
- 15 We do not limit this invention to the structure shown and described, as many modifications may be made within the scope of the appended claims without departing from the spirit thereof.
- 20 What is claimed as new and desired to be secured by Letters Patent is:
- 25 1. A railway car moving device comprising a base having spaced apart front and rear downturned bearing portions, a tooth carried by said base intermediate said downturned portions extending below the lower plane of said downturned portions, a lever of the first class pivotally fulcrumed on said base intermediate said downturned portions, a roller carried by one end of said lever positioned entirely intermediate said front and rear bearing portions.
- 30 2. A railway car moving device comprising a base having a narrowed front portion, spaced apart front and rear downturned bearing portions, a rearwardly extending transverse tooth carried by said base intermediate said downturned portions having its lower portion extending below the lower plane of said downturned portion, a lever of the first class pivotally fulcrumed on said base intermediate said downturned portions and a roller carried by one end of said lever intermediate said front and rear bearing portions.
- 35 3. A railway car moving device comprising a base having a relatively narrow front portion, a turned down portion at the front end of said narrowed portion, a turned down portion at the rear of said base portion, a rearwardly inclined tooth mounted in said base member intermediate said turned down portions and extending entirely thereacross below the lower plane of said turned down portions, a lever of the first class pivotally

fulcrumed on said base intermediate said turned down portions and a roller carried by one end of said lever intermediate said front and rear turned down portions.

In testimony whereof, we hereunto affix ⁷⁰ our signatures.
